UNITED STATES PATENT OFFICE.

ALBERT J. KLETZKER, OF ST. LOUIS, MISSOURI.

BOOK-COVER.

SPECIFICATION forming part of Letters Patent No. 361,950, dated April 26, 1887.

Application filed February 23, 1886. Serial No. 192,875. (No model.)

To all whom it may concern:

Be it known that I, ALBERT J. KLETZKER, of the city of St. Louis, in the State of Missouri, have invented a certain new and useful Improvement in Book-Covers, of which the following is a full, clear, and exact description, reference being had to the accompanying drawings, forming part of this specification, and in which—

10 Figure 1 is a perspective view of an "inside book" with the removable cover thereon. Fig. 2 is a perspective view of the same with one leaf of the cover open. Fig. 3 is an inside perspective view of the cover. Fig. 4 is a perspective view of the inside book.

15 It is not a new thing to bind account-books with light covers and to inclose them in a removable cover when in use, the latter being removed when the account-book is full, or for 20 other reason thrown out of constant use.

My improvement consists in the described construction of the cover and manner of holding it in place upon the inside book.

A is the inside book, the leaves B of whose 25 cover may be made light and without any ornamentation, as they will not be subjected to wear nor be in sight when in use. These leaves B have slots b for the passage of buttons c c' upon the cover C C'. The buttons c each has 30 a single tongue, while button c' is double-tongued.

In order that removable covers of the class 35 to which my invention belongs may operate properly, it is necessary that they should be permitted to slide to a limited extent upon the cover-leaves of the inside book in opening and closing the book. To this end the slots b are formed with their greater length in a direction transverse to the back of the book or parallel 40 with the plane in which the covers move in opening and closing. It is necessary that the buttons which secure the cover-leaves together should be of such a nature as to permit this movement of the covers relatively to each other, 45 while it is at the same time desirable that the former should hold the latter snugly together. These results I accomplish by forming each of a thin shank and a plate spring head or tongue pivoted thereto.

50 The leaves of the cover are made double, each leaf consisting of an outside part, C, and

an inside part, C', with space between them to receive the leaf B of the inside book. The inside part, C', is shown divided into three strips, c², c³, and c⁴, extending lengthwise of the leaf. 55 The strip c² is open at both its long edges, but united with the outside C at both ends. The strip c⁴ is united with the outside part, C, at the outer edge and at both ends, and the strip c³ forms a flap hinged at one long edge to the 60 inner edge of the strip c⁴ and not directly connected to the outside part, C. When the strip c³ is folded down, as seen in Fig. 2, it fills the whole space between the strips c³ and c². The spring-buttons are attached to the part C by 65 rivets D, upon which they turn as pivots. The heads d of the rivets may be made in form of bosses, upon which the book may rest, thus preserving the face of the outside part, C, of the cover from wear. 70

In putting the cover upon the book A, the leaves B are inserted between the parts C and C', and then the buttons c c' are drawn through the slots b and turned across the slots, as seen in Fig. 2. Then the strips or flaps c³ are closed 75 down, as shown in Fig. 2. It will now be seen that the face of the part C' will be flat, except for the part of the strip cut out to have access to the button c', and thus a smooth bearing will be given to the leaves of the book which 80 are next to the part C'.

I have described the inner part, C', of the leaves of the supplementary or removable cover as consisting of three strips; but this is not essential, for it may consist of one or more, the 85 essential feature being the locking device, while the other novelties of the invention have value in their combination with this.

It has been stated that for the purpose of holding the two covers snugly together the buttons are formed of spring-steel plates; but it is obvious that so far as other features of the invention are concerned this is not essential. For example, the slots arranged as described do not depend upon any peculiarity in the construction of the heads of the buttons in order to 90 permit the two covers to slide upon each other. 95

I claim as my invention—

1. The combination, with the book having cover-leaves provided with slots elongated in a direction transverse to the back of the book, 100 of the outside cover having buttons adapted to

pass through said slots and engage the cover-leaves of the book, substantially as and for the purpose set forth.

2. A removable cover having spring-buttons to hold cover of an inside book.

3. The combination, with an inner book having cover-leaves, of an outside removable cover having the strips c^2 and c^4 placed on the inside of the cover-leaves, as described, and having their ends secured to the ends of said cover-leaves, the intermediate strip, c^3 , hinged to the edge of one of the aforesaid strips, and buttons for securing the cover-leaves of the inner book and removable cover together, substantially as set forth.

15

4. The outside or supplemental cover having pockets to receive the cover-leaves of an inside book and spring-catches to engage the same, substantially as set forth.

5. The combination, with an inside book and a removable outside cover, the cover-leaves of the former being provided with slots, of spring catches or tongues secured to the leaves of the removable cover, substantially as and for the purpose set forth.

ALBERT J. KLETZKER.
